FIRE EXTINGUISHING APPARATUS

Ralph M. Padelford, Nevada, Iowa, assignor to Iowa State University Research Foundation, Inc., Ames, Iowa, a corporation of Iowa

Filed Aug. 20, 1963, Ser. No. 303,242

2 Claims. (Cl. 169—1)

This invention relates to fire extinguishing apparatus and method and, more particularly, to an apparatus and method that operates by smothering a fire.

The invention described herein was made or conceived in the course of or under a contract with the United States Atomic Energy Commission.

The invention has particular utility in extinguishing small fires and employs a woven asbestos, cup-shaped member for confining the flammable material. The provision of such a device and the method of use, therefore, constitute an objective of this invention.

Another object of the invention is to provide a novel fire extinguishing device and the method of use thereof wherein an asbestos cup is equipped with unique handle means for developing a unique manipulative procedure relative to small fires.

Other objects and advantages of the invention may be seen in the details of construction and operation set down in this specification.

The invention is described in conjunction with the accompanying drawing, in which—

FIG. 1 is a fragmentary perspective view of an embodiment of the invention;

FIG. 2 is an enlarged fragmentary longitudinal sectional view of the device of FIG. 1;

FIG. 3 is a perspective view, partially broken away, of a modified version of the invention;

FIG. 4 is a sectional view taken along the line 4—4 of FIG. 3;

FIG. 5 is a fragmentary view, partially broken away, of yet another modification of the invention; and

FIG. 6 is a sectional view taken along the line 6—6 of FIG. 5.

In the illustration given and with particular reference to FIG. 1, the numeral 10 designates generally a cup constructed of finely woven asbestos—preferably aluminized—to which is attached an elongated handle generally designated 11. The handle 11 is equipped with a cartridge mechanism generally designated 12, and the assembly of elements 10—12 is seen in the hands of an operator 13.

Referring to FIG. 2, it is seen that the handle 11 is tubular in construction, having a longitudinally-extending bore 14 communicating at one end as at 15 with the interior 16 of the cup 10. The base 17 of the cup is seen to be suitably reinforced by a flexible wire ring as at 18.

The handle 11 is secured within an aperture 19 in the cup 10 by means of suitable lock nuts 20 and 21 threadedly received on the tubular handle 11. Additionally, a rubber washer 22 may be applied to the inner end of the handle 11.

The tubular bore 14 is closed at the outer end by means of a plug 23, also threadedly fixed to the handle 11. Projecting laterally of the tubular handle 11 is a nipple 24 which is threadedly received within a transverse bore 25. It will be seen from FIGS. 1 and 2 that the nipple 24 extends in the direction of the base or closed end of the cup 10. Mounted on the nipple 24 is the cartridge-holding device 12, which is seen to support a cartridge 26. The device 12 communicates with the bore 14 through the nipple 24 and is equipped with a hand screw 27 which is arranged for piercing the cartridge 26. A threaded closure 28 is provided for inserting and removing the cartridge 26. The cartridge 26 preferably contains carbon dioxide or nitrogen, i.e., an incombustible or inert

2

gas, for extinguishing the fire by displacing the oxygen within the fire cup 10. These cartridge ordinarily may be purchased for as little as fifteen cents, and a single cartridge will do the work of several large carbon dioxide extinguishers because all of the inert gas is contained within the fire cup 10. The savings achieved are attractive in that the carbon dioxide or nitrogen fire cup may be recharged for fifteen cents as compared to the six or seven dollars it costs to recharge one 10-pound carbon dioxide fire extinguisher.

A second type of fire cup is seen in FIGS. 3 and 4, with the cup portion again being constructed of woven asbestos and being designated by the numeral 110, the handle portion being generally designated by the numeral 111. The embodiment seen in FIGS. 3 and 4 is employed for transferring burning material from an area where other flammables are stored and where the fire hazard is great. The asbestos cloth wall will "breathe" and allow the safe release of excessive pressure, thereby minimizing the danger of explosion while transferring burning material. However, the asbestos cloth is sufficiently dense to prevent oxygen from entering the cup from the outside to feed the contained fire. In addition, the wall of the cup acts as a fire screen should the burning material be a flammable liquid which might sweep through the wall during transfer.

In the illustration given in FIGS. 3 and 4, the asbestos cup 110 is equipped with a stiff wire ring 112 suitably fastened by means of clips 113 to the closed end of the cup. A flexible wire 114 is woven around the open end 115 of the bag 110, the wire ends terminating at the handle portion in a loop 116—thereby permitting the open end 115 to be closed by drawing on the loop 116.

The handle 111 includes a pair of metal brackets 117 which, at the upper ends thereof, are U-shaped as at 118 to support the cup 110 by engaging the stiff ring 112.

In operation, the wire loop pull ring 116 is pulled to close the open end 115 so as to permit transfer of the flammable material to a remote site. This transfer fire cup extinguishes small fires by depriving them of oxygen and permits the safe transfer of burning material away from hazardous areas where other flammable materials are stored.

A third form of the invention is seen in FIGS. 5 and 6, which includes a cup 210 and a handle 211. The handle 211 includes a flexible wire loop 212 having one end terminating in a pull ring 213, the other end 214 being fixed to the handle 211.

The cup 210 is substantially rigid-walled and is molded from sheet asbestos. The cup 210 is molded so as to provide a groove 215 around the circumference of the cup near the closed top 216. The bottom 217 of the cup is open.

In operation, the handle is applied to the cup, whereupon the cup may be positioned open-mounted downwardly on a fire so as to extinguish the same, the handle being removable as desired.

Each of the fire cups shown and described accomplishes its extinguishing purpose without contaminating the burning material. This is particularly important in a scientific laboratory where even small quantities of material may be worth thousands of dollars—materials that may be ruined by using dry powder, dry chemical, lime graphite, or other extinguishing agents. The cups keep heat and flame contained so as to prevent any nearby flammable liquids or pyroforic materials from igniting and afford protection to the user by containing heat, smoke, fumes, flames and toxic gases which can be produced by laboratory materials.

While in the foregoing specification a detailed description of the invention has been set down for the purpose of explanation thereof, many variations in the details

herein given may be made by those skilled in the art without departing from the spirit and scope of the invention.

I claim:

1. A fire extinguishing apparatus comprising a cup constructed of woven asbestos material and having an open mouth adapted to be face downwardly in extinguishing a fire, a reinforcing ring mounted in said cup generally parallel to and spaced from said mouth, a conduit-providing tubular handle coupled at one end thereof to said cup and communicating with the cup interior and extending laterally away from said cup, said handle being equipped with a cartridge holding device, said device being adapted to confine a cartridge and deliver inert gas therefrom to said handle conduit, said handle being closed at the other end thereof whereby inert gas from said cartridge is directed into said cup.

2. A fire extinguishing apparatus comprising a cup constructed of woven asbestos material and having an open mouth, adapted to be face downwardly in extinguishing a fire, a reinforcing ring mounted in said cup generally parallel to and spaced to said mouth and providing a top for said cup, a conduit-providing tubular handle coupled at one end to said cup adjacent to, but spaced below said ring and communicating with the cup interior, said handle extending laterally away from said cup and being equipped with a cartridge holding device adjacent the laterally ex-

5

tending end thereof, said device supporting a puncturable cartridge confining an inert gas, a puncture means on said cartridge holding device, said cartridge holding device being equipped with a second conduit communicating with the handled conduit to deliver inert gas from said cartridge to the cup interior, said woven asbestos material being capable of flexure to relieve excess pressure resulting from delivery of said inert gas thereto.
